CUTTER FOR CIGAR-TIPS.

1,113,105.

Specification of Letters Patent.

Patented Oct. 6, 1914.

Application filed March 16, 1914. Serial No. 824,861.

To all whom it may concern:

Be it known that I, FELIX DEMAN, a citizen of the United States, residing at 529 West One Hundred and Eleventh street, New York, county of New York, and State of New York, have invented certain new and useful Improvements in Cutters for Cigar-Tips, fully described and represented in the following specification and the accompanying drawings, forming a part of the same.

The present invention relates to a cigar-cutter having a flat case in which a flat slide is movable to sever the tip of the cigar, and the invention consists in a particular construction for the parts by which very few pieces are used in the manufacture of the cigar-cutter and its operation rendered automatic in a large degree.

The construction will be understood by reference to the annexed drawing, in which—

Figure 1 is a side view of the cigar-cutter closed; Fig. 2 is a side view of the cigar-cutter open in readiness for use. Figs. 3 to 6 show the cutter upon an enlarged scale. Fig. 3 represents the cutter with one side *a* removed; Fig. 4 is a view of the upper end of the cutter with the yoke tipped sidewise; Fig. 5 is a longitudinal section on the center line of Fig. 3, with the slide in its upper position; and Fig. 6 is a similar section with the slide moved partially outward.

The case is shown formed with two flat sides *a* and *b*, each having a semi-circular cutting-notch *c* in its lower end and the space between such sides next the cutting-notch being just sufficient for the slide *d* to move freely therein. A cutting perforation *d'* is formed through the slide to operate with the notch *c* when the slide is pushed upwardly.

The flat sides *a* and *b* are connected by marginal flange *e* at the edges and at the upper end, an aperture *f* being formed through such flange at the middle of such end, and the flat side *a* having a beveled tongue *g* bent slightly from its upper end into the said aperture, as shown in Fig. 5.

The upper end of the slide has a lug *h* adapted to project outward through the aperture and has a shallow notch *i* adapted to engage the tongue *g*. Recesses *e'* are formed in the edges of the slide and studs *e''* are inserted through the flange *e* to enter

such recesses and engage their ends to limit the upward and downward movement of the slide.

The outer end of the recess limits the upward movement of the slide and also the projection of the lug *h* through the aperture *f*. The inner end of the recess limits the outward movement of the slide and sets the cutting perforation *d'* even with the notch *c* upon the case.

A leaf-spring *j* is attached by one end to the flat side *b* and sloped abruptly therefrom at its free end toward the side *a* which carries the tongue *g*, and operates to press the slide normally toward such tongue to engage the notch *i* therewith. The end of the lug *h* which projects outward through the aperture *f* is sloped away from the notch in a direction opposite to the slope of the leaf-spring, so that when the notch is disengaged from the tongue and the sloping surface of the lug pressed toward the tongue by the spring *j*, the slide is pushed longitudinally by and between the two sloping surfaces, and such action of the sloping end of the lug thus co-operates with the sloping portion of the leaf-spring to expel the slide from the case, as desired, when the lug is disengaged by the finger from the tongue *g*.

The engagement of the tongue and notch serve to hold the slide within the case, as indicated in Fig. 1, excepting a projection below the notch *c*. A quick shove upon the end of the lug *h* by the finger *m* shown in Fig. 5 serves to disengage the tongue from the notch and to throw the end of the lug upon the sloping surface of the spring, which then operates in practice to propel the slide as far as the sloping portion of the spring extends. The slide, when carried thus far, lies in the position shown in Figs. 3 and 6, and the insertion of the cigar-tip in the perforation or cutting-hole *d'* operates to move such aperture in a line with the notch *c*, in readiness to sever the tip. Pushing the slide inwardly then cuts off the cigar-tip and simultaneously locks the slide in its closed position by the automatic tongue and notch engagement of the lug *h*.

The cutter is especially adapted to be operated with one hand only, by fitting a yoke *k* to the case. Such yoke is shown pivoted in the opposite edges of the case so as to swing or hinge thereon, and is prefer-

ably used with a chain *l*, a portion of which is shown in Fig. 1, which may serve to support the cigar-cutter upon a fob, or elsewhere. By grasping the chain or yoke with one hand, the thumb of such hand can be used to push the lug *h* inwardly by a quick shove, causing the slide to open automatically a sufficient extent to insert the cigar-tip in the aperture *d'*, which draws the slide still farther downward to its full extent before cutting the tip.

The manufacture of these cutters involves the use of very few pieces, and its design renders the locking of the slide automatic when moved upwardly, and the outward movement of the slide equally automatic when the lug *h* is disengaged by shoving it inwardly.

I am fully aware that slides movable in a flat case have been used in the making of cigar-tip cutters, but in such cases the slide has been provided with spiral springs to push it out of the case, or when unprovided with such springs required to be pulled outwardly by the fingers. In my construction, no spiral springs are required to propel the slide out of the case, but the same leaf-spring *j* which serves to engage the lug *h* with the tongue *g*, and which is necessary for this purpose, performs also a new and additional function, by reason of its sloping position, in pushing the slide from the case when the lug *h* is detached from the tongue. I have therefore claimed this special feature of my construction herein.

I claim—

1. In a cigar-cutter, the combination, with a flat cutting-slide having a cutting perforation, of a flat case adapted to inclose the slide movably and having a cutting-notch at its lower end and space, at its upper end only, to permit a slight lateral movement of the slide, the case having an aperture at the upper end, and the slide having a lug to project therefrom with a stop to limit such projection, a tongue formed upon one of the flat sides of the case adjacent to the aperture, and the lug having a notch to engage such tongue and being projected outwardly through the aperture and such projecting end sloped so as to bear obliquely upon the tongue when the notch is disengaged therefrom, and a

leaf-spring attached at one end to the opposite side of the case for pressing the lug to make such engagement, and sloped in opposition to the sloping end of the lug so as to push the lug and slide downwardly when the lug is released from the tongue. 55 60

2. In a cigar-cutter, the combination, with a flat cutting-slide having a cutting perforation, of a flat case having a cutting-notch at its lower end and closing flange at its edges and upper end, with aperture 65 through the flange at such upper end, and fitted to the thickness of the slide at its lower end, and having space at its upper end for a slight lateral movement of the slide, a lug upon the upper end of the slide 70 adapted to project through the aperture in the upper end of the case and having a tongue and notch engagement with one side of the case next such aperture, a leaf-spring having one end attached to the opposite side 75 of the case for pressing the slide to make such engagement, and sloped to crowd the slide downwardly when released from such engagement, the slide having a recess in at least one edge, and the edge of the case 80 having a stud fitted to such recess to restrict the outward movement of the slide.

3. In a cigar-cutter, the combination, with a flat-fitting slide having a cutting perforation, of a flat case adapted to inclose the slide movably and having a cutting-notch at its lower end and an aperture at its upper end, and space between the sides of the case at its upper end to permit a slight lateral movement of the slide, 90 the slide having a lug to project through such aperture and having a tongue and notch engagement with one side of the case, a leaf-spring having one end attached to the opposite side of the case to press such 95 lug into engagement with the case, and a yoke pivoted to the case adjacent to the projecting end of the lug and adapted to support the cigar-cutter while pressing the lug from such engagement. 100

In testimony whereof I have hereunto set my hand in the presence of two subscribing witnesses.

FELIX DEMAN.
